OVERHEAD DOOR

Chauncey Marsh Goodrich, Windsor, Ontario,
Canada

Application January 21, 1937, Serial No. 121,655

4 Claims. (Cl. 20—19)

This invention relates to overhead doors, one of the objects being to mount a door of this type in such a manner that it will operate properly regardless of its width.

5 Specific examples of the invention are illustrated by the accompanying drawing, in which:

Figures 1 and 2 are vertical sections of a door forming the first example, the figures respectively showing the door closed and open.

10 Figure 3 is a similar section of a door forming the second example, dotted lines here showing the open position.

In the first example, laterally spaced tracks 1 right angularly extend horizontally from the top 15 of a doorway 2. Carriages 3 ride these tracks and pivotally suspend a door 4 for the doorway 2. A plurality of laterally spaced radius rods 5 pivotally connect the transverse central portion of the door 4, as at 6, to supports 7 on the other side 20 of the doorway from the extending direction of the tracks 1, these supports being substantially on a level with the top of the door 4.

Powered endless ropes 8 serve to move the carriages 3. When these carriages are moved away from the doorway 2, the door 4 pivots at the points 25 6 and on the carriages 3 while the radius rods 5 swing about the supports 7, the door being consequently elevated to clear the doorway. If further clearance is desired, powered ropes 9 may be arranged to extend down through the doorway 2 and connect with the door 4 at the points 6. In such an instance spring-tensioned ropes 10 may be connected with the ropes 9 at points in line with the top of the door 4, whereby to keep the ropes 9 tightly against the door 4 when the latter is closed. When the ropes 9 are used, the ropes 8 are necessarily pulled only to start the movement of the door, power being applied to the ropes 9 to complete the opening operation and to draw the door tightly to its open position.

40 In the second example of the invention, the same parts are used except that the door is provided with upwardly extending arms 4^a having counterpoises 4^b on their top ends, these counterpoises serving to reduce the forces required to raise the door to its open position.

It is obvious that the width of the door is immaterial, it being possible to suspend the door from any number of points, the door being at the same time centrally supported at any desired number of points by use of the proper number of the radius rods 5.

55 In the case of very wide doors, such as airplane hangar doors, it may be desirable to provide the strut 4^c, shown in the drawing illustrating the second example. This strut may be in the form of a triangular structural element, should extend the width of the door, and be firmly

fixed to the latter's bottom. This will prevent any tendency of the door to warp during opening or closing. As a further precaution the radius rods 5 may be provided with turnbuckles 5^a, illustrated in the case of both examples, it then being possible to individually adjust the lengths of the various radius rods to hold the door in its proper form at all times.

The opening motions imparted to the door by the described arrangement consists first in a lifting motion in a vertical direction and a subsequent swinging and lifting of the door into what is at least approximately a horizontal position. The initial lifting motion is of advantage when snow is banked against the outside of the door.

I claim:

1. The combination of means adapted to travel laterally from a doorway for pivotally suspending a door for the same by its top and means of constant length for pivotally connecting the central portion of said door pivotally to a support on the opposite side of said doorway, respecting the traveling direction of the first named means, adjacent the level of the top of said door. 15

2. The combination of means adapted to travel laterally from a doorway for pivotally suspending a door for the same by its top, means of constant length for pivotally connecting the central portion of said door pivotally to a support on the opposite side of said doorway, respecting the traveling direction of the first named means, adjacent the level of the top of said door, and means for counterpoising said door when the first named means travels away from said doorway and the second named means causes said door to pivot upwardly. 25

3. The combination of means adapted to travel laterally from a doorway for pivotally suspending a door for the same by its top, means of constant length for pivotally connecting the central portion of said door pivotally to a support on the opposite side of said doorway, respecting the traveling direction of the first named means, adjacent the level of the top of said door, means for moving the first named means away from said doorway and other means for applying lift to said door below its top. 40

4. The combination of laterally spaced tracks right angularly extending horizontally from the top of a doorway, carriages riding said tracks and pivotally suspending a door for said doorway and a plurality of laterally spaced rods pivotally connecting the transverse central portions of said door to supports on the other side of the doorway from the extending direction of said tracks, said supports being substantially on a level with the top of said door. 50

CHAUNCEY MARSH GOODRICH.
